UNITED STATES PATENT OFFICE.

WILLIAM E. GREENAWALT, OF DENVER, COLORADO.

ELECTROLYTIC APPARATUS.

1,347,088.

Specification of Letters Patent. Patented July 20, 1920.

Application filed February 1, 1917. Serial No. 145,884.

To all whom it may concern:

Be it known that I, WILLIAM E. GREENAWALT, a citizen of the United States, residing in the city and county of Denver and State of Colorado, have invented certain new and useful Improvements in Electrolytic Apparatus, of which the following is a specification.

The electrolysis of liquids having a gas in solution has always given a great deal of trouble because the solubility of any gas in a liquid is necessarily very small, and the greatest difficulty so far encountered has been to keep the liquid charged with the gas during electrolysis, so that the gas would be taken up in solution by the liquid as rapidly as the gas in the liquid is consumed, fixed, or chemically combined with the liquid by the electrolytic action.

20 The object of my invention is to make it technically practical to charge a liquid with a gas during electrolysis and maintain it charged as rapidly as the gas in the liquid is acted upon by the electric current. A 25 further object of my invention is to make it commercially feasible to produce an acid by combining a gas with a liquid by means of electrolysis.

Frequent attempts have been made, for 30 example, to produce sulfuric acid direct from sulfur dioxide by combining it with water, by means of electrolysis, but all these processes have failed of practical results largely, or entirely, because the gas could 35 not be charged into the liquid as rapidly as the gas dissolved in the liquid was combined with the liquid to form acid. The solubility of any gas in a liquid, especially sulfur dioxide, is necessarily small. If the gas is bubbled into the liquid, during electrolysis, the 40 contact is only momentary, and the conditions for absorption are about as bad as they could reasonably be: besides, the gas is usually wasted and the cell room is usually 45 made unbearable.

If the gas is dissolved in the liquid in a scrubbing tower, which is the usual method of procedure, not enough gas can be absorbed to make the electrolysis effective, for, 50 unless the gas is brought in contact with the electrodes in sufficient amounts, the process will be highly inefficient, and, at best, after a few minutes contact with the electrodes, even with agitation, the operation becomes 55 impractical.

In my invention, the difficulties enumerated are entirely overcome. Not only is the liquid and the dissolved gas brought in intimate and effective contact continuously with the electrodes, but the liquid is at all 60 times maintained charged with the gas, and this charging of the gas may be to saturation, super-saturation, or emulsion, without any waste of gas, or without making the cell room unbearable. A current density 65 having once been established as the most efficient for the solubility of any particular gas in a liquid, this current density can always be maintained, because the conditions for maximum efficiency can always be maintained. The electrolyte need never become 70 impoverished for the want of gas.

My invention is best described by referring to the accompanying drawings, in which Figure 1 shows a general longitudinal section: Fig. 2, a detail cross section: Fig. 3, a detail longitudinal section: Fig. 4, a detail plan: Figs. 5 and 6, details of the electrical connections and insulations between electrodes and conducting bars of opposite polarity: Fig. 7, a detail of the disks: Figs. 8 and 9, a cross section and longitudinal section, respectively, of a detail of the shaft: Fig. 10, a longitudinal section of a modified apparatus: Fig. 11, a detail cross 85 section of Fig. 10: Fig. 12, a detail longitudinal section of Fig. 10: and Figs. 13 and 14, a detail cross section and longitudinal section, respectively, of the shaft in Fig. 10.

Referring to the accompanying drawings, 90 1 shows an electrolytic chamber adapted to contain a liquid and to confine a gas over the liquid. 2 is a gas generator, communicating with the electrolytic chamber 1, by means of the pipe 3. In the electrolytic 95 chamber are located the electrodes 4 and 5, either of which may be anodes and either cathodes. Above the electrodes is a shaft 6, on which are mounted disks 7, and which rotates in the bearings 8, when driven by 100 the motor 11. The electrodes are submerged in the liquid, and part of the disks are submerged in the liquid and part immersed in the gas over the liquid.

The disks are fixed on the shaft by collars 105 12, (Figs. 8 and 9) fitting between the disks 7 and the washers 13, and maintained tight by the nut 14. The collars 12, and the washers 13, are made of some material unaffected by either the gas or the liquid, and pref-

erably a non-conductor of the electric current, so that the shaft is unaffected by any operation of the apparatus. The disks are preferably made of hard rubber: this is light, sufficiently strong, and unaffected by either the liquid, the gases, or the electric current.

The electric current is supplied to the electrodes by means of the terminals 33 and 34, and the bars 15 and 16 in the bottom of the tank, and electrical connection is made with the electrodes by letting the electrodes rest on these conducting bars. The electrodes are held in position by the side pieces 17, which may be of wood, and having saw-cuts 18, or grooves, to receive the ends of the electrodes. The arrangement and insulation of the electrodes is shown in detail in Figs. 2, 3, 4, 5, and 6. One end of the electrode rests on its corresponding conducting bar, say, 15, while the other end rests on an insulation plate, preferably of hard rubber, 19, and this plate, in turn, rests on the opposite conducting bar. Referring to Figs. 5 and 6, for example, the electrode 4 rests on the conducting bar 16, while the opposite end rests on the insulation plate 19, which, in turn, rests on the bar 15. The electrodes 5 rest on bar 15, but are insulated from bar 16 by the plates 20. A current, therefore, entering through the bar 16 would pass to the electrode 4, and being insulated from bar 15, would pass through the liquid from electrode 4 to electrode 5, and then to the bar 15 on which 5 rests directly, but is insulated from 16.

It is preferred to arrange the cells so that the gas will pass from one cell to the next while the liquid flows in the opposite direction. The flow of gas, for example, would be from the gas generator 2 through the pipe 3 into cell 1 then through the pipe 22 into cell 21, and so on until it is sufficiently impoverished: the liquid, flowing in the opposite direction, would flow from cell 21 through the pipe 23 into cell 1 and out through pipe 24. If, in addition to passing the gas over the liquid, it is desired to pass it through the liquid, it is exhausted from the top of the chamber through the pipe 25, and by means of the blower 26 is forced into the pipe 27, into the distributing pipes 28 and into the liquid to pass up through the liquid and agitate it.

The detail of the disk is shown in Fig. 7. It is preferably made with small holes 30, and serrations 31, so that as the disk rotates some of the liquid is more readily elevated into the gas above and some of the gas submerged in the liquid. The spraying of the liquid into the gas is also facilitated by the holes and serrations. If desired, grooves 32, may also be made on the face of the disks to assist in intimately mixing the gas and liquid.

Referring to the modified apparatus, as shown in Figs. 10 to 14 inclusive, it will be seen that one set of electrodes are fixed, as in Fig. 1, while the rotating disks are the opposite electrodes. The electric current is supplied to the disks through the shaft 6, which, when large currents are to be used, may be made hollow and an electrical conductor, such as a round copper bar, fitted tightly in the hollow shaft. The current is supplied to the shaft by means of a mercury contact as shown at 40. The disks rotate between the stationary electrodes, and are preferably made of hard lead, and having proper electrical connections with the shaft. The disks 10 are held in position by the washers 13, which in this case may also be conductors, and these, in turn, are held in position by the collars 12, which may be made of iron containing a large percentage of ferro-silicon to make it acid proof, although it could also be made of hard rubber. Outside of the collars is a rubber insulation covering, which may be made of hard rubber piping, cut to fit between the washers 13.

The electric current, entering the shaft 95 at 40, is distributed to the various disks, which are all the time rotating; from the disks the current passes through the liquid and causes the desired electrolytic action, passes to the electrodes 4, to the conducting bars 15, and out through the terminal 33. Both terminals, in this case, are of the same polarity.

Referring, now, more particularly to Figs. 1 to 9 inclusive, and having in mind the electrolysis of copper sulfate solutions obtained from leaching ores, and containing more or less iron, the operation of the apparatus may be described as follows: It is assumed that there are a number of cells in series, and that the copper solution to be electrolyzed is introduced into the last cell of the series, and the gas, which we will assume as sulfur dioxide, is introduced into the first cell of the series. There are three essential conditions, or objects, to be kept in view in the electrolysis of impure copper solutions, under these conditions: viz: the deposition of the copper; the regeneration of the acid; the maintaining of the iron in the ferrous condition by means of the reducing action of the sulfur dioxide. In the electrolysis of copper solutions containing iron, the iron is converted into the ferric condition by the oxidizing action of the oxygen released at the anode, and if the ferric iron is allowed to accumulate in the electrolyte, efficient deposition is impossible because the ferric iron is reduced at the expense of the deposited copper.

Assuming the apparatus to be in operation on copper sulfate solution coming directly from the ore, that is to say on a solution in which the iron is entirely or almost entirely in the ferrous condition, copper will be deposited at almost the theoretical efficiency, but in the deposition of the copper, the oxygen released at the anode converts the iron into the ferric condition, and this in turn, attacks the deposited copper. Small amounts of ferric iron in the solution are not particularly harmful, but if allowed to accumulate, it makes the copper deposition impractical. This is obviated in my apparatus by continually reducing the ferric iron as rapidly as formed by continuously bringing portions of the electrolyte in intimate contact with sulfur dioxide above the electrolyte. As the copper is deposited, and sulfuric acid regenerated, and ferric iron produced, the disks over the electrodes agitate the liquid so as to keep fresh portions of the electrolyte in contact with the electrode and simultaneously spray a portion of the liquid into the gaseous atmosphere over the liquid, while at the same time a certain amount of the sulfur dioxide gas is forced into the liquid. The disks, arranged with the perforation and serrations, facilitate this action. The disks, in rapidly rotating, fill the chamber with a fine spray, and this spray hitting the sides and top of the cell is further subdivided, and in dropping to the bottom the spray is still further subdivided and intimately mixed by again coming in contact with the rotating disks. The flow of gas from the gas inlet to the gas outlet still further aids this action. The interior of the chamber, therefore, in the upper part, may be regarded as an intimate mixture of the gas and the sprays of liquid, more or less in the form of a mist, and represents the best conditions possible for effective absorption. As the liquid is sprayed into the gaseous atmosphere a large surface, or liquid film is also exposed on both sides of the disks, and as the disk surface, in the aggregate, is large, this is an important factor. The disks, in rotating from the gas into the liquid, inevitably trap a certain amount of the gas in the perforation and serrations, which is submerged in the liquid, and assists still further in effective absorption and agitation. The liquid may, therefore, be charged with the gas to any degree desired; to saturation, super-saturation, or even emulsion, and this represents the best possible conditions for the electrolysis of a liquid and a gas in the liquid. It is evident, that under these conditions, the ferric salts may be maintained reduced in the electrolyte: or at any rate what virtue sulfur dioxide may possess it possesses at its maximum efficiency.

65 The apparatus is preferably made in two

sections, so that the upper section, with the agitating or spraying device, may be elevated with chain blocks, and the electrodes exposed. The copper cathodes may then be removed without difficulty and new ones inserted.

If it is desired to circulate the gas through the liquid by means of the gas pump 26, and connecting pipe lines 25, 27, and 28, the gas is preferably distributed in the bottom by 75 the distributing device, 35, shown in Fig. 2.

Referring now more particularly to Figs. 10 to 14 inclusive, the apparatus will be described as applied to the process of converting sulfur dioxide into sulfuric acid. In 80 carrying out the process, the liquid contained in the bottom of the cell is preferably a dilute solution of sulfuric acid. Sulfur dioxide gas, from the gas generator 2, is introduced into the cell, and is confined over 85 the liquid. In the electrolysis of dilute sulfuric acid, that is to say in the electrolysis of water, oxygen is released at the anode: Manifestly, therefore, if the anode is rapidly rotated in the liquid containing sulfur dioxide in solution, the maximum oxidizing effect will be obtained, and this is the end sought for. The oxygen in its nascent state, released at the surface of the rapidly rotating anode, comes in contact with large 90 volumes of the liquid and with relatively large quantities of the gas dissolved in the liquid, and the process obtains its highest possible efficiency. As the disks rotate the surface of the disks is alternately in the gas 95 and liquid, so that as the surface of the disks emerge from the liquid with much of the gas in proximity to the disks consumed, they are immersed in the gas where the sulfur dioxide is again replenished, both by immersion in the gas itself and by the intimate mixing of the gas and liquid and by the agitation of the liquid. It is evident, therefore, that the process is continuous and efficient, because, primarily, the liquid is charged 100 with the gas as rapidly as the gas in the liquid is consumed, or fixed, by electrolysis.

It has been found that the anodes, especially, under these conditions, are only very slowly disintegrated, and need only be replaced at comparatively long intervals. In the operation of the apparatus, the stronger acid solution is preferably brought in contact with the strongest gas, and concentrated, or strong, acid is withdrawn at the 105 rate that a weaker solution, from the previous cell, is introduced. In metallurgical work, strong acid, as a rule, is not desired, so that the strength of acid in the liquid is preferably kept at its maximum electrical 110 conductivity.

Gases to promote the reactions desired may also be introduced into the chamber in addition to the gases directly involved in the electrolytic action.

The temperature of the electrolyte is not so important as under ordinary condition; the solubility of the gas is not so material. In the electrolysis of sulfur dioxide to produce sulfuric acid, the temperature of the liquid was kept very low to get a reasonable solubility of the gas in the electrolyte. In my apparatus this is not necessary for the gas is continually supplied to the liquid as rapidly as consumed, and the gas may exist in the liquid to super-saturation, or emulsion.

In operating the apparatus there is intended to be a slight suction inwardly. This may be produced by a suction fan in the last cell of the series (not shown) by any of the well known methods.

I claim:

1. In electrolytic apparatus, a chamber having a gas inlet and a gas outlet and adapted to contain a liquid and to confine a gas over the liquid, stationary electrode plates submerged in the liquid, a shaft located above the stationary electrode plates and above the liquid, disks mounted on the shaft dipping into the liquid and immersed in the gas over the liquid, means for rotating the disks with sufficient rapidity to spray the liquid into the gas above it, and means for passing an electric current through the electrodes and liquid charged with the gas.

2. In apparatus for subjecting a liquid and a gas to the action of an electric current, a lower section adapted to contain the liquid and the electrodes, a removable upper section engaging the lower section and forming therewith a sealed chamber, means for introducing a gas into the upper section, means for charging the liquid in the lower section with the gas confined in the upper section, and electrical means for causing a chemical reaction between the gas and the liquid.

3. In apparatus for subjecting a liquid and a gas to the action of an electric current, a lower section adapted to contain the liquid and the electrodes, a removable upper section engaging the lower section and forming therewith a sealed chamber, means for introducing a liquid in the lower section, means for introducing a gas in the upper section, rotary means within the chamber for charging the liquid in the lower section with the gas in the upper section, and electrical means for causing a chemical reaction between the liquid and the gas.

4. In electrolytic apparatus, a chamber having a gas inlet and a gas outlet and adapted to contain a liquid and to confine a gas over the liquid, electrodes within said chamber, spraying means arranged to spray the liquid into the gas over the liquid and transversely to the flow of the gas, means for causing a flow of gas transversely to the liquid sprays, and means for passing an electric current through the liquid.

5. In apparatus for subjecting a liquid and a gas to the action of an electric current, a lower section adapted to contain the liquid and the electrodes, a removable upper section engaging the lower section and forming therewith a sealed chamber, means for flowing a stream of liquid through the lower section, means for flowing a stream of gas through the upper section, means for charging the liquid with the gas confined over it, and electrical means for causing a chemical reaction between the liquid and the gas.

6. In electrolytic apparatus a chamber adapted to contain a liquid and to confine a gas over the liquid, means within said chamber for charging the liquid with the gas over it, means within the said chamber for agitating the liquid, electrodes submerged in the liquid having one end resting on a conducting bar submerged in the liquid and in electrical contact while the other end of the electrodes is electrically insulated, and means for passing an electric current through the electrodes and through the liquid charged with the gas.

7. In electrolytic apparatus having vertical electrodes, means above the electrodes for agitating the electrolyte.

8. In electrolytic apparatus a stationary chamber adapted to contain a liquid and to confine a gas over the liquid, a rotatably mounted shaft within said chamber, spraying means partially immersed in the gas and partially submerged in the liquid mounted on said shaft, means for protecting the shaft from the corrosive action of the liquid and the gas, means for electrically insulating the shaft from the electrodes, and means for passing an electric current through the liquid.

9. In electrolytic apparatus, a chamber having a gas inlet and a gas outlet and adapted to contain a liquid and to confine a gas over the liquid, means for flowing a gas from the gas inlet to the gas outlet, means for taking the gas from above the liquid and forcing it through the liquid, and means for passing an electric current through the liquid.

10. In electrolytic apparatus, a chamber adapted to contain a liquid and to confine a gas over the liquid, conducting bars submerged in the liquid, electrodes resting on said conducting bars, means independent of the electrical conducting bars for maintaining the electrodes in position, means for electrically insulating the electrodes of one polarity from those of the opposite polarity, and means for passing an electric current to the conducting bars and electrodes and through the liquid.

11. In electrolytic apparatus, electrodes resting on submerged conducting bars of both polarities in the electrolyte, means for electrically insulating the electrodes of one

11. In electrolytic apparatus, a chamber adapted to contain a liquid capable of reacting with sulfur dioxid and to confine sulfur dioxid gas over the liquid, means within said chamber for charging the liquid with the sulfur dioxid, agitating means within said chamber for bringing the liquid charged with sulfur dioxid in effective contact with the electrodes, means for passing an electric current through the liquid charged with the sulfur dioxid whereby the sulfur dioxid is converted into sulfuric acid, and means for supplying sulfur dioxid to the space above the liquid as rapidly as the sulfur dioxid in the liquid is converted into sulfuric acid.
12. In electrolytic apparatus, a chamber adapted to contain a liquid capable of reacting with sulfur dioxid and to confine sulfur dioxid gas over the liquid, means within said chamber for charging the liquid with the sulfur dioxid, agitating means within said chamber for bringing the liquid charged with sulfur dioxid in effective contact with the electrodes, means for passing an electric current through the liquid charged with the sulfur dioxid whereby the sulfur dioxid is converted into sulfuric acid, and means for supplying sulfur dioxid to the space above the liquid as rapidly as the sulfur dioxid in the liquid is converted into sulfuric acid.
13. In electrolytic apparatus, a chamber adapted to contain a liquid and to confine a gas over the liquid, means within said chamber for charging the liquid with the gas over it, means within said chamber for agitating the liquid, and means for replenishing the gas above the liquid as rapidly as the gas is charged into the liquid, and means for passing an electric current through the liquid.
14. In electrolytic apparatus, a chamber adapted to contain a liquid and to confine a gas over the liquid, means located wholly above the electrodes for charging the liquid with the gas over it.
15. In electrolytic apparatus, a chamber adapted to contain a liquid and to confine a gas over the liquid, means for spraying the liquid transversely of the chamber, and means for causing a flow of gas longitudinally with the chamber.
16. In apparatus for subjecting a liquid and a gas to the action of an electric current, a lower section adapted to contain the liquid and the electrodes, a removable upper section engaging the lower section and forming therewith a sealed chamber, means for introducing a liquid in the lower section, means for introducing a gas in the upper section, means for intimately mixing the liquid with the gas confined over it, and means for passing an electric current through the electrodes.
17. In electrolytic apparatus, a stationary chamber adapted to contain a liquid in the lower portion and to confine a gas in the upper portion, a hollow shaft rotatably mounted having spraying means within the chamber, an electrical conductor within the hollow shaft, and means for passing an electric current through the liquid.
18. In apparatus for subjecting a liquid and a gas to the action of an electric current, a lower section adapted to contain the liquid and the electrodes, a removable upper section engaging the lower section and
19. In electrolytic apparatus stationary vertical electrodes resting on electrical conductors submerged in the electrolyte.
20. In electrolytic apparatus electrodes of both polarities resting on electrical conductors submerged in the electrolyte.
21. In electrolytic apparatus means for confining a gas over the electrolyte, and means above the electrodes for spraying the electrolyte into the gas.
22. In electrolytic apparatus having a gas confined over the electrolyte, means for spraying the electrolyte into the gas, and means for agitating the electrolyte with the gas.
23. In electrolytic apparatus having sulfur dioxid confined over the electrolyte, means for agitating the electrolyte with sulfur dioxid.
24. In electrolytic apparatus stationary vertical electrodes resting on electrical conductors submerged in the electrolyte and spacing pieces for maintaining the electrodes in position.
25. In electrolytic apparatus having a gas confined over the electrolyte, means for agitating the electrolyte with the gas.
26. In apparatus for subjecting a liquid and a gas to the action of an electric current, a lower section containing the liquid and the electrodes, a removable upper section engaging the lower section and forming therewith a sealed chamber, means for introducing a gas into the upper section, means for spraying the liquid in the lower section into the gas in the upper section, and means for passing an electric current through the electrodes.
27. In apparatus for subjecting a liquid and a gas to the action of an electric current, a lower section containing the liquid and the electrodes, a removable upper section engaging the lower section and forming therewith a sealed chamber, means for introducing a gas into the upper section, means for treating the liquid in the lower section with the gas in the upper section, and means for passing an electric current through the electrodes.
28. In electrolytic apparatus for subjecting a liquid and a gas to the action of an electric current, a lower section adapted to contain the liquid and the electrodes, a removable upper section engaging the lower section and forming therewith a sealed chamber, means arranged for resting the

electrodes on electrical conductors submerged in the electrolyte, means for introducing a gas into the upper section, means for introducing a liquid in the lower section, 5 means for treating the liquid in the lower section with the gas in the upper section, and electrical means for causing a chemical reaction between the liquid and the gas.

29. In electrolytic apparatus having in-
10 soluble anodes, removable stationary vertical electrodes resting on electrical conductors submerged in the electrolyte and making electrical contact therewith.

30. In electrolytic apparatus, a tank
15 adapted to contain the electrolyte, an electrical conductor submerged in the electrolyte, stationary removable electrodes resting on the electrical conductor and making electrical contact therewith, and means for

passing an electric current through the con- 20 ductor and the electrodes.

31. In electrolytic apparatus a chamber adapted to contain a pool of liquid and to confine a gas over the liquid and having a gas inlet and a gas outlet and a liquid inlet 25 and a liquid outlet, means for causing a flow of gas through the chamber, means within the chamber for mixing the liquid and the gas, means for agitating the liquid with the gas by withdrawing the gas from the upper portion of the chamber and introducing it into the liquid in the lower portion, and means for electrolyzing the liquid.
